MEANS FOR RESILIENTLY MOUNTING
VANES OR FRANGIBLE PUMP ELE-
MENTSStephen G. Orban, Bloomfield, N. J., assignor to
Bendix Aviation Corporation, Teterboro, N. J.,
a corporation of Delaware

Application June 20, 1951, Serial No. 232,512

4 Claims. (Cl. 230—149)

1

This invention relates generally to means for applying a spring force to a relatively soft, frangible element or body and more particularly has to do with a novel saddle-like button arrangement interposed between a spring and an element made of carbon, graphite or other relatively soft and frangible material whereby the force exerted by the spring may be transmitted to the element. The instant invention has particular utility when employed to maintain the sliding vane of a dry air rotary pump in operative contact with the rotor thereof.

It has become common practice to utilize sliding vanes made of graphite, or carbon, in dry air rotary pumps, especially where such pumps are designed and constructed to operate at relatively high speed.

Due to the relatively soft and frangible character of the material of such sliding vanes, the spring loading of the vane so as to maintain it in operative relationship with the rotor of the pump has presented many difficulties. For example, in instances where the spring has been placed directly in contact with the sliding vane, the relative hardness of the metal of the spring and the carbon or graphite of the vane has resulted in the rapid wearing or breaking of the vane at the place where the spring contacts the vane. Thus, frequent inspection and replacement of the vane has been required in order to insure the continued positive operation of the pump. In other instances, where a resilient pad has been interposed between the end of the spring and the vane, the high temperatures developed during the operation of the pump have resulted in the rapid deterioration or "breakdown" of the pad. Moreover, the use of a resilient pad has also been found objectionable in that in instances where the bonding agent securing the pad to the vane fractures, the pad, being resilient, does not provide a stable platform between the spring and vane with the result that the vane is apt to shift or move out of alignment with its guides. It is apparent under such conditions the vane may break or wear unevenly, thereby resulting in the "breakdown" or inefficient operation of the pump.

The instant invention has for one of its objects the provision of means for mounting the carbon or graphite vane of a rotary pump so as to overcome the foregoing difficulties.

Among other objects, the present invention contemplates a vane assembly embodying novel means whereby the vane may be operatively positioned relative to the rotor of the pump and in the event the bonding agent securing the vane

2

to the assembly fractures, the vane will be supported in its proper position without any undesirable shifting or moving of the vane relative to the guides thereof.

5 A further object of the instant invention is to provide a stable mounting platform for a carbon or graphite element whereby a spring force may be transmitted to the element.

The above and other objects and features of 10 the present invention will appear more fully hereinafter from a consideration of the following description taken in connection with the accompanying drawings wherein one embodiment of the invention is illustrated by way of example. It 15 is to be expressly understood, however, that the drawings are for illustration purposes only and are not to be construed as defining the limits of the invention.

In the drawings wherein like reference characters refer to like parts in the several views:

Fig. 1 is a fragmentary side view, partially in section, of a rotary air pump embodying the novel means for mounting the vane as contemplated by the instant invention;

25 Fig. 2 is a fragmentary end view showing a vane assembly in elevation and its relationship with the rotor of the pump;

Fig. 3 is an enlarged section through the vane assembly;

Fig. 4 is a plan view of the vane; and

30 Fig. 5 is an enlarged side view of the saddle-like button.

Referring now to the drawings, Fig. 1 illustrates a rotary dry air pump of a conventional type consisting, in general, of a power unit 10 and an air pumping assembly 11 constructed and arranged to be mounted to, and driven by, the power unit 10.

35 In this instance, power unit 10 comprises an electric motor 12 suitably mounted and enclosed within a hollow housing 13. An end wall 14, closing one end of housing 13, is provided with an extension 15 in which is mounted an electrical connector or plug 16 whereby the power unit 10 may be connected into a suitable electrical circuit for the operation of motor 12.

40 The air pumping unit 11 comprises a casing 17 having head and end walls 18 and 19, respectively, that are adapted to be mounted to opposite sides of casing 17. Head wall 18 is secured to the casing 17 by bolts 20 which pass through registered openings in a flange 21 and a flange 22 formed integrally with casing 17 and head wall 18, respectively.

45 In order to mount the pumping assembly 11 to the power unit 10, end wall 19 is provided

with a lateral extension 23 that extends partially into the open end of housing 13. A snap ring 24 is engaged within an annular recess 25 formed in housing 13 adjacent its open end, and a bearing ring 26, slidable within housing 13, is adapted to engage the inner surface of the snap ring 24. A series of bolts 27 pass through registered openings provided in bearing ring 26, end wall 19 and a flange 28 formed on casing 17 to the end that the tightening of nuts 29 carried by bolts 27 brings the bearing ring 26 into engagement with snap ring 24 thereby securely mounting the casing 17 to the housing 13.

Head and end walls 18 and 19, respectively, cooperate with a bore formed in casing 17 to define a cylindrical pump chamber 30. Motor 12 is provided with a shaft 31 that extends through a central opening 32 in end wall 19 and across pump chamber 30, where it is journaled in a sealed bearing 33 mounted in head wall 18. Suitable seals 34 are provided to prevent any lubricant utilized in bearing 33 from leaking into the pump chamber 30.

An eccentric rotor 35 is secured to shaft 31 for rotation therewith and carbon seals 36 and 37 are provided in head and end walls 18 and 19, respectively, to sealingly engage the sides of rotor 35.

Head wall 18 is provided with a suitable air inlet (not shown) and an air outlet 39 shown in Fig. 1, which communicate with passageways 40 and 41, respectively, formed in casing 17, as shown in Fig. 2. Passageways 40 and 41, in turn, communicate by way of ducts 42 and 43, respectively, with a bore 44 formed in casing 17 intermediate the passageways 40 and 41. A slot 45 formed in casing 17 between bore 44 and pump chamber 30 communicates the former with the latter.

Bore 44 is adapted to receive a cylindrical insert 46 having angularly disposed, flat side surfaces 47 and 48 and a vertical slot 49. A vane 50 slidably mounted in slot 49 extends through slot 45 and is adapted at its end 51 to sealingly contact the rotor 35. Thus, vane 50 divides slot 45 into passageways 45a and 45b which communicate with inlet and outlet passageways 40 and 41 respectively.

In order to apply a resilient pressure to the vane 50 and thereby sealingly engage the end 51 thereof with rotor 35, a plurality of spring assemblies, generally indicated by the reference character 53, are mounted in casing 17 and are disposed so as to engage the vane 50 at spaced intervals along the length thereof. As shown in Fig. 1, the instant pump assembly is provided with two spring assemblies 53, and since each spring assembly 53 is identical in structure, only one is described in detail.

To house the spring assembly 53, casing 17 and insert 46 are provided with registered, vertical bores 54 and 55, respectively. A cover plate 56, removably mounted to casing 17 by a bolt 57, has fixedly secured thereto a stud or post 58 that is adapted to be snugly received into vertical bore 54. To prevent leakage through bore 54, post 58 is provided medially of its length with an annular groove 59 in which is mounted a rubber sealing ring 60. The inner end of post 58 serves as a seat for one end of a compression spring 61 that is utilized to apply the required resilient load to vane 50.

As above set forth, the engagement of the other end of spring 61 to vane 50 has heretofore presented many problems. Thus, where spring

61 has been placed directly in contact with vane 50, the relative hardness of the materials has resulted in a rapid breakdown of the vane and where a resilient pad has been interposed between the spring 61 and vane 50 the high operating temperature and frequent breaking of the bonding agent has similarly resulted in inefficient pump operation.

The instant invention overcomes the difficulties heretofore experienced by providing a novel saddle-like button 62 that is adapted to be interposed between the spring 61 and vane 50 and which serves to transmit the pressure from the former to the latter.

As shown in Figures 3 and 5 the saddle-like button 62 comprises a cylindrical body 63 having diametrically opposed, depending flanges 64 which define a transverse channel 65, substantially U-shaped in cross-section, at one end of the body 63. The channel 65 is dimensioned so as to receive one end of the vane 50 therein with the end of the vane 50 in abutment with the transverse wall of channel 65 and with the interior surfaces of flanges 64 snugly embracing the opposite side walls of the vane 50. The body 63 may be centrally recessed as at 66 and a central aperture 67 extending between the channel 65 and recess 66 is adapted to receive shank 68 of a rivet or stud 69. Rivet 69 is secured to body 63 by upsetting the end of the shank 68 thereof, or by some suitable bonding agent. A convex head 70 formed on rivet 69 is thereby positioned in channel 65 between the flanges 64, where it engages a concave recess or depression 71 shown in Fig. 4 and formed in the upper surface 72 of the vane 50. A suitable bonding agent, such as sodium silicate, applied to the inner surfaces of flanges 64 and the convex head 70 of rivet 69 serves to securely fasten the body 63 to the vane 50.

Medially of its length, the body 63 is provided with an annular peripheral flange 73 which forms a seat for the lower end of spring 61. Thus, spring 61 is operatively positioned between the lower end of post 58 and the flange 73 of the saddle-like button 62.

It will be seen from the foregoing description that all that is necessary to carry out the teaching of the instant invention is that the saddle-like button 62 have a channel for the reception or housing of the upper end of the vane 50; that there be provided a cooperating abutment 70 and depression 71 formed in the channel and vane, and a means 73 for seating the spring in engagement with the saddle-like button 62.

Due to the foregoing arrangement of parts, when motor 12 is actuated to rotate the rotor 35 in a clockwise direction as viewed in Fig. 2, air is drawn into the pumping unit 11 through the inlet provided in head wall 18. From the inlet, the air passes through inlet passageway 40 and duct 42, into bore 44 where surface 47 deflects the air through passageway 45a into the pump chamber 30. Air being discharged from pump chamber 30 by the rotor 35 leaves through passageway 45b where it is deflected by surface 48 through duct 43 into outlet passageway 41 and from thence to outlet 39. A one-way flapper valve 75 operatively positioned in outlet 39 permits air under pressure of the pump to pass from the outlet while preventing back flow of air into the pumping unit 11.

As hereinbefore set forth, the vane 50 is resiliently urged into contact with rotor 35. It is apparent, therefore, that as the eccentric rotor

35 revolves, spring assemblies 53 operate to maintain the end 51 of vane 50 in sealing contact with the rotor 35 to the end that communication between passageways 45a and 45b is prevented.

In the event the bonding agent securing the saddle-like button 62 to vane 50 fractures or fails in any way, the flanges 64 prevent any transverse movement of the saddle-like button 62 relative to the vane 50, while the engagement of the convex head 70 of the rivet 69 with the concave recess 71 formed in vane 50 prevents any longitudinal movement of vane 50. The saddle-like button 62, therefore, forms a relatively stable platform through which the force exerted by spring 61 is transmitted to the vane 50. Thus, it is apparent that vane 50 continues to reciprocate in slot or guide 49 without shifting or canting relatively thereto and the pump assembly 11 continues to operate without loss of efficiency.

From the foregoing description of the construction and operation of the present invention, it will be apparent that a novel means for maintaining the sliding vane of a rotary type dry air pump in sealing contact with the rotor thereof has been provided in which the several objects of the instant invention have been achieved.

I claim:

1. The combination with a relatively soft frangible element and a spring for applying a force to said element, of a button adapted to be interposed between said element and spring for transmitting force exerted by the spring to the element comprising a body, depending flanges on said body defining a U shaped channel at one end of said body for the reception of said element, said flanges serving to prevent transverse movement of said element in said channel, a convex abutment in said channel, a concave recess in said element for engagement with said convex abutment to prevent longitudinal movement of said element in said channel, and a peripheral flange on said body for engagement with said spring.

2. In a pump having a rotor; the combination comprising a vane slidably contacting said rotor, a plurality of springs for maintaining the vane in contact with the rotor of said pump, a plurality of saddle-like buttons; each of said buttons secured to one end of said vane and engaged by an end of one of said springs, each of said buttons including a cylindrical body, depending flanges on diametrically opposed sides of said

body defining a transverse channel at one end of said body to snugly receive one end of said vane, a peripheral flange on the body medially of its length for engagement by said one end of said spring, and a convex abutment mounted in said channel; said vane having a plurality of concave recesses formed in said one end of said vane, and the convex abutment of each button engageable in one of said concave recesses, and bonding means in the channel of each of said buttons securing said vane in said saddle-like buttons.

3. The combination defined by claim 2 in which each of said saddle-like buttons includes a recess formed in its cylindrical body at the opposite end from said flanges, a central aperture extending between the recess and the channel defined by said flanges, a rivet having a shank and a convex head, said rivet being mounted in said body into the shank thereof in said central aperture and the convex head thereof in said channel so as to engage in one of the concave recesses formed in said one end of the vane.

4. In combination, a rotor, a vane having one end slidably contacting said rotor and a concave recess formed in the opposite end thereof, a saddle-like button comprising a cylindrical body, depending flanges on diametrically opposite sides of said body forming a transverse channel at one end thereof to snugly receive said opposite end of said vane and prevent transverse movement of said vane relative to said body, a convex abutment in said channel and engageable with the concave recess formed in the end of said vane to prevent longitudinal movement of said vane in said channel, a peripheral flange on said body disposed medially of its length, and resilient means engageable with said peripheral flange for maintaining said body in engagement with said vane and said vane in contact with said rotor.

STEPHEN G. ORBAN.
